CLAIM

The ornamental design for connector for fluid supply for patient infusion, as shown and described above.

DESCRIPTION

FIG. 1 is a top, front, right side perspective view of a connector for fluid supply for patient infusion, according to a first embodiment;

FIG. 2 is a bottom, rear, left side perspective view of a connector for fluid supply for patient infusion, according to a first embodiment;

FIG. 3 is a front elevational view of a connector for fluid supply for patient infusion, according to a first embodiment;

FIG. 4 is a top, front, right side perspective view of a connector for fluid supply for patient infusion, according to a second embodiment;

FIG. 5 is a bottom, rear, left side perspective view of a connector for fluid supply for patient infusion, according to a second embodiment; and,

FIG. 6 is a front elevational view of a connector for fluid supply for patient infusion, according to a second embodiment.

The article shown in broken lines in the drawings is intended to show the claimed design while in use; the matter in broken lines forms no part of the claimed design.
